UNITED STATES PATENT OFFICE.

AMÉDÉE FAYOL, OF BORDEAUX, FRANCE.

CHROMATIC-PRINTING PRESS.

SPECIFICATION forming part of Letters Patent No. 447,507, dated March 3, 1891.

Application filed January 2, 1891. Serial No. 376,471. (No model.) Patented in France January 2, 1889, No. 195,139.

To all whom it may concern:

Be it known that I, AMÉDÉE FAYOL, residing at Bordeaux, Department of Gironde, France, have invented an Improvement in 5 Chromatic-Printing Presses, of which the following is a specification, and for which I have obtained Letters Patent in France for fifteen years, No. 195,139, of January 2, 1889.

My invention relates to an improvement in 10 printing-presses, the object being to print advertisements or other parts of daily papers, periodicals, or the like in colors at the same time that the remainder of such paper is printed in black.

15 My invention consists in the mechanism hereinafter described, said mechanism comprising original means for moving the parts of the type which should print in colors by utilizing the centrifugal force resulting from 20 the speed of the printing-cylinders.

The accompanying drawings illustrate my invention, wherein—

Figure 1 is a longitudinal section of a type-cylinder of an ordinary press, showing my 25 device within the cylinder in side view. Fig. 2 is a longitudinal section of the cylinder and the therein-contained mechanism. Fig. 3 is a cross-section on line 1 2 of Figs. 1 and 2. Fig. 4 is a cross-section on line 3 4 of Figs. 1 30 and 2. Fig. 5 is an end view of the said cylinder, the left-hand end of Figs. 1 and 2 being illustrated. Fig. 6 is a top view of the cam mechanism shown in Fig. 5. Fig. 7 is a longitudinal section of a modification. Fig. 35 8 is a cross-section on line 5 6, Fig. 7. Fig. 9 is an end view of the left-hand end of Fig. 7. Fig. 10 is a side elevation of the collar k' shown in Fig. 7 and a cross-section of its shaft b .

40 The type-cylinder a turns with its arbor b , which, extending through the cylinder-heads a' a' , revolves in the journals b' , that are fixed on the frame of a press. The type-cylinder has a hole in the side to allow the passage in and out of the carrier d , which supports the type or cut c for producing the color-impressions, said carrier d being moved by the mechanism within the cylinder. The type-carrier d slides in and out in a box f , 45 which is fixed on the arbor b , its mouth entering an opening in the cylinder a , as in Fig. 2. The box f is connected at its inner end

with a clasp f' , which partly embraces the shaft b , as in Fig. 4, and which is secured to said shaft by screws f'' . The type c or printing-surface is united rigidly to its support d by means of screws e' e'' , that are carried by the movable piece d . This color-type carrier d is provided with interior bosses d^2 d^2 , which receive a rod g , to which I attach the extremity 55 of a lever h . This lever h is keyed to an arbor k , which is placed parallel to the arbor b , and is held in two supports or collars k' k' , which are fastened to the arbor b . The arbor k is fastened to the cylinder a , and extends beyond one end of the cylinder. To this end of the arbor k a stationary arm i is fastened, which, by means of a screw i' , pushes a lever l , carrying at one end a friction-roller l' , against a stationary cam x , which is connected with 60 the stationary journal b' of the arbor b . A spring r , Fig. 3, fastened to the inner end of the arbor k , insures the constancy of contact of the roller l' and of the cam x , the tension of which it is easy to regulate by the screw 65 i' , thereby regulating the strength of the color-impression by increasing or lessening the throw which it imparts to the type c . The periphery of the cam x is so formed that, through the medium of the lever l , which follows the outline of the cam, the type-carrier d and type c in one movement is lowered 70 below the plane of the fixed type A when the cylinder receives the black ink and then raised above the plane of the type A when the 75 said movable type is to receive the colored ink and finally brought into the plane of the type A when it is to give the impression.

During the normal working of the press the cylinder a possesses a great velocity, which 80 results in a centrifugal action, which carries the type-carrier d and its type outward. The cam x therefore only regulates these movements of the type-carrier d and the thereon-contained type.

In starting the machinery the spring r , bearing against the arbor of the lever l and the cam x , compels the type-carrier d and its support to execute the proper intermittent movements. To facilitate the mounting and dismounting of the type-carrier d , the pivot g is put into the support d by means of a long flexible rod j , ending in a plug j' , which is screwed into an outer cylinder-head a^2 . Said 85 90 95 100

cylinder-head a^2 is also a support for the arbor k . To afford an entrance of the pivot g and to serve as a guide for the same to its seat, I introduce the tube j^2 , which is held in place by the head a' and the outer box f of the type-carrier d . By removing the rod g the type-carrier d can be lifted out of the cylinder.

In the modification shown in Figs. 7, 8, 9, 10 and 10 the case f , which contains and guides the type-carrier d , is large enough to permit of placing between it and the arbor b , but independently of this latter, a sort of compound connecting-rod n , designed to connect the pivot g with the head of the lever h . This connecting-rod comprises, as is seen, an articulated T-piece to the pivot g and a catch or fork n^2 , embracing the extremities of the horizontal bar of the T and surrounding the arbor b . The lower part of this fork n^2 is coupled together with the lever h , which is keyed on the arbor k and which oscillates in the collar-supports $k' k'$. On the outer side of the outer cylinder-head a^2 is secured to the end of the arbor k the piece i , which, as before described, regulates the position of the type-carrier. The box f may be fixed within the cylinder a by the two outer screws $a^3 a^3$, the heads of which are sunk into the cylinder a , and the two inner screws $a^4 a^4$, screwed through the bottom of the box and butting against the interior wall of the cylinder, thereby setting the box firmly in place. In this manner the arbor k may govern one, two, 35 or more type-carriers. Likewise one, two, or more arbors k may be put within the cylinder.

der, so that it will be possible to place the type-carrier at any point on the circumference of the cylinder. The plates thus moved by the working of the press may be inked in any convenient manner. Nevertheless, I prefer for inking the movable inker, which I made the object of another application on the 29th day of December, 1890, Serial No. 376,027.

Having now described my invention, what I claim is—

1. The combination, in a color-printing press, of the type-cylinder a with the type-carrier d placed therein and with mechanism 50 within the type-cylinder, substantially as described, for drawing said type-carrier inward, and with mechanism, substantially as described, for enabling centrifugal force to move said type-carrier outward, as specified. 55

2. The combination of the hollow type-cylinder with the reciprocating type-carrier d placed therein and with the lever h , arbor k , lever l , spring r , and stationary cam x , all arranged for operation substantially as herein shown and described. 60

3. The combination of the type-cylinder a with the inner box f , reciprocating type-carrier d , rod g , lever h , spring r , arbor k , arm i , lever l , and stationary cam x , all arranged 65 substantially as herein shown and described.

In witness whereof I have hereunto set my hand in presence of two witnesses.

AMÉDÉE FAYOL.
